[57] CLAIM

The ornamental design for a combined feeder and waterer for pets, as shown and described.

DESCRIPTION

FIG. 1 is a top plan view of a combined feeder and waterer for pets showing my new design;

FIG. 2 is a left end elevational view thereof;

FIG. 3 is a side elevational view thereof, the opposite side being a mirror image of the side shown;

FIG. 4 is a right end elevational view thereof;

FIG. 5 is a bottom plan view thereof; and

FIG. 6 is a perspective view thereof.

FIG. 1

FIG. 2

FIG. 3

FIG. 4
